UNITED STATES PATENT OFFICE.

PAUL C. RAWLS, OF DES MOINES, IOWA.

CRYSTAL-RECTIFIER.

1,211,754.

Specification of Letters Patent.

Patented Jan. 9, 1917.

Original application filed July 6, 1914, Serial No. 849,298. Divided and this application filed December 30, 1914. Serial No. 879,801.

To all whom it may concern:

Be it known that I, PAUL C. RAWLS, a citizen of the United States, and resident of Des Moines, in the county of Polk and State 5 of Iowa, have invented a certain new and useful Crystal-Rectifier, of which the following is a specification.

My invention relates to crystal rectifiers used in high frequency oscillation detectors 10 in wireless telegraphy or telephony.

The object of my invention is to provide an improved crystal rectifier of simple and inexpensive construction of increased efficiency and sensitiveness and of great durability or ruggedness, which is so mounted and arranged that it is not likely to get out of adjustment readily; and further in this connection to provide a crystal rectifier having a large number of points of maximum 20 sensitiveness which may be easily found by the operator and maintained in working position.

My invention consists in the construction, arrangement and combination of the various 25 parts of the device, whereby the objects contemplated are attained, as hereinafter more fully set forth, pointed out in my claims and illustrated in the accompanying drawings, in which;

30 Figure 1 shows a side elevation of a crystal rectifier and means for mounting the same, embodying my invention. Fig. 2 shows a vertical longitudinal sectional view of a portion of the mechanism. Fig. 3 35 shows an enlarged sectional view of the contacting portions of my improved crystal rectifier. Fig. 4 shows an enlarged detail face view of that portion of the crystal rectifier in which the zinkite crystal is contained, and Fig. 5 shows an enlarged detail 40 sectional view, illustrating the contacting faces of the crystals of my improved crystal rectifier.

This application is a divisional of my co- 45 pending application No. 849,298, filed July 6, 1914.

It will, of course be understood that my improved crystal rectifier is employed as a part of a mechanism for detecting oscillations in carrying on the operations of wireless telegraphy and telephony.

In the exemplification of my invention illustrated in the accompanying drawings, I have used the reference numerals 10 and 11 55 to indicate generally the binding posts of

my improved crystal rectifier, which are mounted on a suitable support 12. Mounted in one of the posts 10 or 11 is a horizontally arranged adjustable rod 13, having on one end thereof an operating head 14, and on the other end thereof an eccentrically arranged cup 15, which receives a zinkite crystal 16, and which is retained within the cup 15 by means of a quantity of mercury amalgam 17 or the like. In the other binding post is a 60 tube 18, having suitably mounted in it, a cylindrical body 19, which is provided with a rod 20, extending through the tube 18, and having on its end an operating head 21. An extensible coil spring 22 is received within 65 the tube 18, and is adapted to yieldingly engage the body 19 and a stop 23 for yieldingly pressing the body 19 longitudinally in a direction toward the post 10.

On the upper end of the body 19 is 70 screwed a sleeve 24, on which is a laterally extending arm 25, which carries a chuck 26. The arm 25 extends in the opposite direction from the sleeve 24. At one end, the arm carries the chuck 26, and to its other end is secured a contractile coil 27, which is operatively connected with an adjustable collar 28 on the tube 18. The collar 28 may be adjusted by means of a set screw 29. The chuck 26 is designed to carry another crystal, 80 which is preferably a piece of copper pyrites 30, which is mounted within a cup shaped container 32, and is held therein by means of a quantity of mercury amalgam 31. On the cup 32 is an arm 33 adapted to be 90 held and gripped by the chuck 26. The posts 10 and 11 are connected by the wires 34 and 35 in a proper circuit.

Several improvements are accomplished by my improved crystal rectifier, one of 95 them being the arrangement of the two counteracting springs 27 and 22, so arranged that when the arm 25 is slightly rotated, the spring 27 is stretched and after the copper pyrites crystal is in contact with the zinkite 100 crystal, as shown for instance in Figs. 3 and 5, there will be a yielding pressure upon it, first in a direction toward the zinkite crystal and second, in a rotary direction relative to its contact point on the zinkite crystal, 105 whereby an improved contact point is made between the crystals. By rotating the head 14, any part of the zinkite crystal may be brought into actual contact with the copper pyrites crystal.

Another substantial improvement accomplished by my improved crystal rectifier, is in the construction of the face, which is first flattened and smoothed, and then it is cut or scored transversely in different directions, as illustrated for instance in Fig. 4, whereby the raised points are left between the grooves, or cuts, or scores. These raised points are shown in exaggerated form in Fig. 5, and are indicated by the reference character 36. What I use is a zinkite crystal having an artificially smooth and polished surface, which is preferably artificial and regularly scarified or scored by means of draw filing or fine sand-papering in two or more different directions, whereby a plurality of very fine regular points are left on the polished surface. In this connection it may be mentioned that a number of smooth polished surfaces will give the same or better results, but necessitates the use of a much greater pressure in holding the other member of the rectifier against the zinkite crystal, which will in many instances cause the other member, which is frequently of softer material than the zinkite crystal to be crushed. The object in slightly scarifying the surfaces of the zinkite crystal is to obtain rectification with less pressure and with the same or uniform result over the entire surface of the zinkite crystal.

I find that improved results are obtained by using the copper pyrites crystal with a rounded point, as shown in Fig. 5, and the zinkite crystal with the large number of points 36, as shown in said figure, insomuch as that when the crystals are in the form shown, all of the raised points of the zinkite crystal are uniformly sensitive, and it is therefore easy for the operator, in adjusting these two crystals relative to each other, to

readily obtain an adjustment of maximum efficiency and rectification.

It will be understood that some changes may be made in the construction and the parts of my improved crystal rectifier, particularly in the method of mounting the crystals, without departing from the essential features and purposes of my invention, and it is my intent to cover by this application any such changes which may be included within the scope of my claims.

I claim as my invention.

1. In a crystal rectifier, the combination of a sleeve, means for supporting the sleeve, a body portion slidably mounted in the sleeve, a spring for normally extending the body portion in one direction from the sleeve, a transverse arm on the outer end of the body portion, a crystal holder at one end of the transverse arm, and a spring connected to the arm and adjustably mounted on the sleeve, for the purposes stated.

2. In a crystal rectifier, the combination of a crystal holder, a spring for normally projecting it toward the opposite crystal, and a second spring arranged in opposition to the first and also capable of applying a lateral tension to the crystal.

3. A crystal rectifier, comprising the combination of two adjacent crystals, one having a relatively blunt point, and the other having a smooth flat polished surface provided with minute substantially regular and uniform projections, the blunt point being arranged to contact with said flat surface.

Des Moines, Iowa, December 22, 1914.

PAUL C. RAWLS.
